Inventor:

John M. Kelly

By Young, Young
Attorneys.

UNITED STATES PATENT OFFICE.

JOHN M. KELLY, OF MANITOWOC, WISCONSIN.

BAG-CLEANING APPARATUS.

1,388,722.

Specification of Letters Patent. Patented Aug. 23, 1921.

Application filed September 21, 1920. Serial No. 411,691.

To all whom it may concern:

Be it known that I, JOHN M. KELLY, a citizen of the United States, and resident of Manitowoc, in the county of Manitowoc and 5 State of Wisconsin, have invented certain new and useful Improvements in Bag-Cleaning Apparatus; and I do hereby declare that the following is a full, clear, and exact description thereof.

10 My invention relates to new and useful improvements in apparatus for cleaning bags, especially cement bags or others from which it is normally difficult to remove the portions of the contents which cling to the 15 sides when said bags are emptied.

The principal object of the invention is to simplify and improve the construction of the apparatus illustrated in my United States Patent No. 1206856, issued December 20 5, 1916. I have found that it is preferable to agitate each individual bag independently of the other bags which are being cleaned instead of shaking all of the bags as in the apparatus shown in this patent.

25 Therefore it is an additional object of the invention to provide an apparatus of this character with a plurality of stationary bag holding elements and employing an independent bag striking and agitating means 30 for use in connection with each of said elements.

It is still another object of the invention to provide a simply constructed means for holding and mounting the beater arms 35 which comprise the bag agitating devices.

With these and other objects in view the invention resides in the novel features of construction, combination and arrangement of parts which will be hereinafter more particularly described and claimed.

40 In the accompanying drawings,

Figure 1 represents a vertical transverse sectional view taken substantially on the plane of the line 1—1 of Fig. 2.

45 Fig. 2 is a horizontal section through the cleaning apparatus, and

Fig. 3 is a detail horizontal or transverse section on the plane of the line 3—3 of Fig. 1.

50 Referring more particularly to the drawings, it will be seen that the preferred embodiment of the invention includes a suitable rectangular horizontally elongated casing 1 having hinged and movable top and side 55 wall portions 2 and 3 respectively and adapt-

ed to contain all of the agitating and suction parts of the apparatus. Extending horizontally within the casing 1 and longitudinally thereof is a pair of frame supporting bars 4, the same being spaced apart a distance substantially equal to the normal width of a cement bag. The several bag holding frames, each of which consists of a substantially inverted U-shaped member 5 having the free ends of its arms disposed in sockets in the supporting bars 4, are arranged in suitably spaced parallel relation so that when the portions 2 and 3 of the casing are removed, bags may be readily slipped on or removed from the frames.

70 The frame supporting bars 4 being spaced from the bottom of the casing 1 are also adapted to receive and support a tray 6, the longitudinal side portions of which are inclined downwardly toward a central trough 7. The intermediate portion of the trough 7 has an outlet opening 8 which communicates with a suction fan casing 9 whereby the material shaken from the bags and deposited on the tray 6 may be drawn into said casing 9 and discharged therefrom through a suitable conduit 10 to a receiving bin 11.

75 The suction means within the casing 9 consists of a rotary fan 12 driven from any suitable source of power located externally of the casing 1. This power is translated to the fan 12 by a pulley carrying drive shaft 13 and a fan shaft 14, these shafts being geared together by bevel pinions or the like 15.

80 The means for shaking and agitating the bags which are disposed on the stationary holding frame 5 is located within each of said frames and consists of a beater mechanism comprising a central shaft 16 extending longitudinally of its bag holding frame, and a plurality of diametrically extending beater arms 17. All of the arms of each of the beaters, which arms are disposed one above the other as shown in Fig. 1, are located in substantially the same plane, and when the apparatus is at rest, in the plane of their bag holding frame, so that the bags may be readily placed on or taken from the several frames 5. The shafts 16 that carry the beater arms 17 are longitudinally slit to provide like sections 16^a and 16^b between which said arms may be clamped with the aid of clamping bolts 18 (see Fig. 3). The beater arms 17 are each preferably construct-

ed of a single piece of relatively rigid wire bent into substantially rectangular shape.

Inasmuch as in the use of the apparatus the shafts 16 are designed to oscillate in order that the arms 17 may be forcibly engaged with the opposite sides of the bags, the ends of the shafts are journaled in suitable bearings, the bearings for the upper ends of the shafts being carried by the bag holding frames 5 as indicated at 19, whereas the lower ends of the shafts are disposed in bearings formed in a bearing strip 20. Disposed at one side of the bearing strip 20, which is substantially parallel with the bars 4, and slidably engaged therewith is a reciprocating bar 21. A plurality of pins 22 extend from the bar 21 and loosely receive the ends of cranks 23, one of which is carried by the lower end portion of each of the shafts 16. One end of the reciprocating bar 21 is connected with a pitman 24, the same being in turn fixed to an eccentric strap 25 mounted in a customary manner on an eccentric 26. Referring to Fig. 2 it will be seen that this eccentric is carried by a transverse driven shaft 27 disposed within the casing 1 and connected with the drive shaft 13 by means of sprockets and a sprocket chain 28. Provision is made for clutching the sprocket 30 of the shaft 27 thereto so that the beating mechanism may be operated at will. Any desired means may be employed for manipulating the clutch 29, such as the manually controlled clutch arm 30 in Fig. 2.

Various changes may be made in the form and proportion of the different parts of the invention and in the manner of assembling the same without departing from the principles thereof or sacrificing any of its advantages.

I claim:

1. In an apparatus of the class described, a supporting base, a bag holding frame on the base, a shaft journaled in said frame, beater arms extending from the shaft, and means for oscillating the shaft to intermittently engage the beater arms with a bag disposed on said frame. 45

2. In an apparatus of the class described, a supporting base; a bag holding frame on the base, a shaft journaled in said frame, radially extending beater arms carried by the shaft, all of said arms being in substantially the same plane, and means for oscillating the shaft. 50

3. In an apparatus of the class described, a supporting base, a substantially inverted U-shaped bag holding frame, the arms of the base thereof being in substantially the same plane, a shaft journaled within said frame, radially extending beater arms carried by the frame, all of said arms being in substantially the same plane, which plane may be caused to coincide with the plane of said frame, and means for oscillating the shaft. 65

4. In an apparatus of the class described, a stationary supporting base, a substantially U-shaped bag holding frame having the ends of its arms secured in said base, a bearing strip located adjacent said supporting base, a shaft having one end journaled in said bearing strip and the other end in the base portion of the U-shaped bag holding frame, beater arms extending from said shaft, and means for rocking said shaft. 70

In testimony that I claim the foregoing I have hereunto set my hand at Manitowoc, in the county of Manitowoc and State of Wisconsin.

JOHN M. KELLY.
